(57) CLAIM

The ornamental design for a foldable golf trolley, as shown and described.

DESCRIPTION

FIG. 1 is a front left side perspective view for a foldable golf trolley, showing our new design in an open configuration; FIG. 2 is a rear left side perspective view of FIG. 1 thereof; FIG. 3 is a front elevational view of FIG. 1 thereof; FIG. 4 is a rear elevational view of FIG. 1 thereof; FIG. 5 is a left side perspective view of FIG. 1 thereof, the right-side perspective view being a mirror image; FIG. 6 is a top left side perspective view of the foldable golf trolley of FIG. 1, in the folded configuration, without the remote handset thereof; FIG. 7 is a front elevational view of FIG. 6 thereof; FIG. 8 is a rear elevational view of FIG. 6 thereof; FIG. 9 is a left side perspective view of FIG. 6 thereof, the right-side perspective view being a mirror image; FIG. 10 is a top plan view of FIG. 6 thereof; and, FIG. 11 is a bottom plan view of FIG. 6 thereof. The broken lines indicate portions of the foldable golf trolley, which form no part of the claimed design. The remote shown grayed out in the figures and surrounded by broken lines show environment and forms no part of the claimed design.
